DESIGN FOR A WALL BRACKET

Harry P. Sharits, Denver, Colo.

Application June 9, 1947, Serial No. 139,535

Term of patent 3½ years

(Cl. D33—3)

To all whom it may concern:

Be it known that I, Harry P. Sharits, a citizen of the United States, residing in the city and county of Denver, and State of Colorado, have invented a new, original, and ornamental Design for a Wall Bracket, of which the following is a specification, reference being had to the accompanying drawing, forming part thereof.

In the drawing:

Fig. 1 is a perspective view of a wall bracket embodying my novel design; and

Fig. 2 is a side elevation of the wall bracket of Fig. 1.

I claim:

The ornamental design for a wall bracket, as shown.

HARRY P. SHARITS.
